UNITED STATES PATENT OFFICE.

JOHN WILLIAMSON, OF LOUISVILLE, KENTUCKY.

DESIGN FOR A PANEL FOR MANTELS.

SPECIFICATION forming part of Design No. 12,751, dated February 7, 1882.

Application filed November 11, 1881. Term of patent 14 years.

To all whom it may concern:

Be it known that I, JOHN WILLIAMSON, of Louisville, in the county of Jefferson and State of Kentucky, have invented a new Design for 5 Decorative Panels for Mantels; and I do hereby declare that the following is a full, clear, and exact description thereof, reference being had to the accompanying drawing, and to the letters of reference marked thereon, which forms 10 part of this specification.

The drawing hereto annexed represents a mantel-piece having side decorations representing trees, birds, and their nests. The vertical panels A are within the margins of the 15 beads B, which are located on opposite sides of the fire-place C. These panels I decorate with figures representing trees, on the branches of which may be birds and birds' nests, as shown; or any other suitable design may be 20 impressed or etched on the said panels.

The leading feature of my design consists in mantel-piece panels A, having suitable figures etched on their surfaces.

The etching or roughing of the figures gives brilliancy to them and boldness to my design, 25 whatever figures may be adopted.

I am aware that mantel-piece panels have been painted so as to represent various designs; but the painted panels do not present the beautiful effect which is obtained by the etching or 30 scratching of the figures into the metallic surfaces of the newly-designed panels.

I claim—

The design for a mantel herein described, consisting of a wooden frame-work, bearing 35 etched or engraved panels surrounded by ornate moldings, substantially as shown and set forth.

In testimony that I claim the foregoing as my own I affix my signature in presence of two 40 witnesses.

JOHN WILLIAMSON.
